VICTOR E. NELSON, OF DETROIT, MICHIGAN, ASSIGNOR OF FORTY-NINE ONE-HUNDREDTHS TO ALFRED T. HARROW, OF DETROIT, MICHIGAN.

INTERNAL-COMBUSTION ENGINE.

1,195,070.

Specification of Letters Patent. Patented Aug. 15, 1916.

Application filed February 29, 1912. Serial No. 630,633.

To all whom it may concern:

Be it known that I, VICTOR E. NELSON, a citizen of the United States, residing at Detroit, county of Wayne, State of Michigan, have invented a certain new and useful Improvement in Internal-Combustion Engines, and declare the following to be a full, clear, and exact description of the same, such as will enable others skilled in the art 10 to which it pertains to make and use the same, reference being had to the accompanying drawings, which form a part of this specification.

This invention relates to internal combustion engines, more particularly to that type of engine in which the explosive charge is introduced into a chamber and compressed prior to its introduction to the explosion chamber, of which the two-cycle engine is 15 an example, and an object of the invention is an engine in which the explosive mixture entering the compression chamber contains at all times a substantially uniform percentage of explosive fluid and in which the 20 throttling of the charge takes place between the compression chamber and the explosion chamber, instead of prior to its entrance to the compression chamber as is the usual practice, whereby the carbureter or other 25 source of supply of said mixture is practically un-alterable as to the volume it is capable of supplying.

A further object of the invention is the provision of means whereby the charge in 30 the compression chamber is maintained in a uniform gaseous state.

In throttling the charge prior to its entrance into the compression chamber, the percentage of gasoline or other volatile oil 40 in the mixture is altered so that the charge is either richer or poorer as the case may be. In such cases it is the usual practice to so adjust the carbureter or mixing valve that the percentage of gasoline in the charge, 45 when the carbureter is in the full-open position, is such as to produce the best results attainable with the particular engine experimented with. If inferior results, as less speed and power, be desired the charge 50 entering the compression chamber is lessened and usually a poorer mixture produced.

In the invention herein disclosed, the carbureter is not provided with a throttle but

is otherwise of an ordinary type and provided with the usual means for altering the volume of flow of gasoline by which the percentage thereof required in the mixture to produce the most effective explosion may be provided and in throttling the engine 55 more or less of such effective charge is admitted to the explosion chamber thus approximating the results attained in steam engines as the mixture in the compression chamber, at the time of its introduction into 60 the explosion chamber, is always under like pressure as hereinafter shown.

In connection with the above described arrangement, means are provided for maintaining the charge in the compression chamber in a uniform gaseous state whereby condensation of the charge in said chamber with its attendant difficulties is obviated.

These and further objects and novelties of the invention are hereinafter more fully 75 described and claimed.

In the drawings—Figure 1 is a vertical section of an engine embodying my invention. Fig. 2 is a detail of the throttle valve. Fig. 3 is a detail of a modification of the 80 invention.

Similar characters refer to similar parts throughout the drawings and specification.

The engine shown is of the two-cycle type and the cylinder 1 is provided with an inlet port 2 and an exhaust port 3 of the usual form. Within the cylinder is a piston 4 arranged to reciprocate therein the movement of which opens and closes said ports and the lower end of the cylinder is open to the compression chamber 5 as is also usual in this type. The chamber 5 is in communication with the inlet port of the cylinder through and by means of the passageway 6 and the flow of gas therethrough is controlled by 95 the throttle valve 7. The chamber 5 is also provided with a port 8 with which a carbureter 9 is to be connected. The carbureter may be of any approved form but is not to be provided with the usual throttle valve but 100 is to be provided with means for adjusting the quantity of gasoline supplied to the air passage in order that the proper mixture may be provided under various atmospheric conditions. The passageway 10 between the 105 carbureter and the chamber 5 is provided with an automatic check valve 11 so arranged as to open during the time the

charge is being drawn into the chamber and to close during the time the charge is being compressed as is usual in this type of engine.

It has heretofore been the practice, in engines of this type to throttle the charge as it enters the compression chamber, the end sought being increased or decreased speed and power as occasion demands in the operation of the engine. The desired results have not been satisfactorily attained due principally to the fact that the gaseous mixture condenses to a greater or less extent in the compression chamber and succeeding charges entering the explosion chamber are too rich in gasoline causing mis-firing, etc., even when the inflowing charge is throttled down to the minimum. To overcome this difficulty, I have provided the compression chamber with a chambered plate 12 and by means of the pipe 13 connecting the water jacket 14 near the upper end of the cylinder with the chamber in the plate, the plate becomes heated and such vapor as may condense on the walls of the chamber flows by gravity on to the hot plate and is again immediately vaporized. The charge in the compression chamber is, therefore, continuously in a uniform gaseous state during the operation of the engine. Also, in throttling the charge as it enters the chamber, a further difficulty is involved resulting in an engine that is deficient in operation. If the charge flowing into the compression chamber is throttled down to a minimum, in the usual manner, it is evident that the chamber will not be so completely filled with the explosive mixture as would be the case if the throttle were fully open. The pressure in said chamber during the compression of the mixture will therefore not be as great as it would if the chamber was completely filled. To illustrate, if the pressure in the chamber be ten pounds per square inch when the engine is running with the throttle fully open, it frequently happens that less than three pounds per square inch is produced when the charge is throttled to a minimum or thereabout. It is, therefore, believed evident that a uniform unvarying result in the throttling of the engine is impossible under such conditions as the pressure of the charge is never uniform.

In the engine herein shown, no throttling of the charge may take place prior to or during its entrance into the compression chamber and the chamber is therefore always uniformly filled by each inflowing charge and the pressure produced in the chamber is always uniform. The charge that enters the chamber always contains a substantially uniform percentage of gasoline such as is required to produce the most effective result when exploded in the cylinder and to produce those varying conditions in the operation of

the engine, such as increased or decreased speed and power as the occasion demands, more or less of this uniform effective charge is allowed to enter the explosion chamber through and by means of the throttle valve 70 7. It therefore becomes evident that, with the described arrangement of the various parts, a uniform dependable result may always be attained with the throttle set at any predetermined point and that the principal difficulties heretofore encountered in the operation of engines of the type described are obviated. 75

While the throttle valve may be of any approved form, I prefer to use the valve 80 shown which consists of a cone shaped seat 20 located in the opening leading to the port 2 and provided with a number of apertures corresponding to the apertures 21 in the cone shaped valve member 22, as shown 85 in Fig. 2. Opposite the port 2 the cylinder wall is provided with a threaded opening 23 through which the valve may be inserted when assembling the parts and said opening is closed by a nut 24 through an aperture in which the stem 25 of the valve projects. A packing nut 26 is provided for the stem and the projecting end thereof is provided with an operating lever 27 by which it may be rotated on its seat and the 90 apertures therein closed or opened as may be required in the operation of the engine. The stem is also provided with a coiled spring 28 and a collar 29. The collar is loose on the stem and engages the inner face 100 of the nut 24 which compresses the spring and yieldingly holds the valve on its seat.

The water chamber 14 surrounding the cylinder may be supplied from any convenient source and in the manner usual with 105 combustion engines and the pipe 13 is connected to that part of the chamber 14 containing water of the highest degree of temperature in order that the plate 12 may be kept hot for the purpose stated. The pipe 110 13 enters the chamber in the plate 12 by an upwardly extending part 15 and the outlet from the said chamber is formed in like manner thereby trapping a portion of the water in the chamber. It is also to be understood that the plate or the walls of the compression chamber 5 may be heated by the 115 exhaust gases from the cylinder, as shown in Fig. 3, without departing from the spirit of this invention, the essential characteristic 120 of this portion of the invention being a means for maintaining the charge in the compression chamber in a gaseous state by means of heat.

Having thus described my invention and 125 its mode of operation, what I claim and desire to secure by Letters Patent of the United States is—

1. In an internal combustion engine, a cylinder provided with inlet and exhaust 130

- ports, a piston therein, a chamber into which the explosive mixture is introduced, a source of supply of said mixture un-alterable in the volume it is capable of supplying and 5 arranged to drain into said chamber, means for maintaining the mixture in the chamber in a gaseous state, a passageway connecting said chamber with the inlet port of the cylinder, and a valve controlling said passageway.
2. In an internal combustion engine, a cylinder provided with inlet and exhaust ports, a piston therein, a chamber into which the explosive mixture is introduced, a 15 source of supply of said mixture un-alterable in the volume it is capable of supplying and arranged to drain into said chamber, means for maintaining the mixture in the chamber in a gaseous state, means whereby the mixture 20 may be introduced into the explosion chamber, and means for altering the volume of mixture so introduced.
3. In an internal combustion engine, a cylinder provided with inlet and exhaust ports, a piston therein adapted to open and close said ports, a compression chamber into which the explosive mixture is introduced by the movement of the piston, a source of supply of said mixture substantially un- 25 alterable in the volume it is capable of supplying and arranged to drain into said chamber, a passageway between the compression chamber and said inlet port, a valve controlling said passageway, means 30 for maintaining the mixture in a gaseous state in the compression chamber.
4. In an internal combustion engine, a cylinder provided with inlet and exhaust ports, a reciprocating piston therein, a 35 chamber into which the explosive mixture is alternately introduced and compressed by the movement of the piston, said movement of the piston also opening and closing the ports in the cylinder, means for maintaining the mixture in the chamber in a gaseous state, means whereby the mixture may be introduced into the explosion chamber, means for altering the volume of mixture so introduced, and means whereby the 40 pressure of the mixture at the time of said introduction is always uniform.
5. In an internal combustion engine, a cylinder provided with inlet and exhaust ports, a piston therein, a chamber, means 45 for supplying the chamber with a uniform gaseous mixture, means for maintaining the mixture in the chamber in a gaseous state,
- means whereby the explosive mixture may be introduced into the explosion chamber, means for altering the volume of the mixture so introduced, and means whereby the pressure of the mixture at the time of said introduction is always uniform. 60
6. In an internal combustion engine, a cylinder provided with inlet and exhaust ports, a reciprocating piston therein adapted to open and close said ports, a chamber open to said cylinder within which the explosive mixture is alternately introduced and compressed by the movement of the piston, 65 means whereby the pressure produced by said compression movement is always uniform, a passageway connecting said chamber and the inlet port of the cylinder, a valve controlling the passageway, and 70 means for heating the chamber.
7. In an internal combustion engine, a cylinder provided with inlet and exhaust ports, a reciprocating piston therein adapted to open and close said ports, a chamber open 75 to said cylinder within which the explosive mixture is alternately introduced and compressed by the movement of the piston, a source of supply of said mixture practically fixed as to the volume of the mixture it is 80 capable of supplying and arranged to drain into said chamber, means for applying heat to said chamber, a passageway connecting the chamber and the inlet port, and a valve comprising an apertured cone-shaped seat, 85 a correspondingly apertured cone-shaped valve head, and means for yieldingly holding the valve head on its seat. 90
8. In an internal combustion engine of 95 the two-cycle type, a compression chamber, means for supplying the compression chamber with an explosive mixture practically uniform in volume and percentage of explosive fluid, means for vaporizing condensed mixture in the chamber, said means comprising a chambered plate forming the bottom wall of the chamber and means for introducing heated fluid thereinto, a passageway between the compression chamber 100 and the inlet port of the cylinder, and a throttle valve controlling said passageway. 105

In testimony whereof, I sign this specification in the presence of two witnesses.
